UNITED STATES PATENT OFFICE.

ARTHUR M. HOOD, OF INDIANAPOLIS, INDIANA.

EXCAVATOR.

Application filed January 8, 1925. Serial No. 1,137.

The object of my invention is to produce an excavator of the dipper type in which the digging swing and forward crowd is accomplished by a single cable and the return lift and resistance to forward crowd is accomplished by an independent coordinated means.

The accompanying drawing illustrates my invention, said drawing being a side elevation, largely diagrammatic in character, of an embodiment of my invention.

In the drawing 10 indicates a suitable supporting structure, as for instance, a truck which may be motorized, the truck 15 being provided with a turn table 11, an anchorage mast 12 and a motor 13 equipped with two winding drums 14 and 15, all being of common construction and the axis of the turn table 11 being vertically beneath 20 the upper end of the anchorage mast 12. The above described construction may be of any ordinary well known character.

Supported upon turn table 11 is an upwardly and outwardly extended boom 16 25 supported at a desired inclination from the upper end of mast 12 by a stretcher bar 17 and suspension cables 18. Mounted at the outer end of boom 16 is a sheave shaft 20 upon which are journaled two sheaves 21 30 and 22, which, for convenience of illustration, are shown in the drawing as of slightly different diameter, although in actual practice they are most conveniently of the same diameter.

Boom 16 is conveniently formed of two parallel laterally spaced channels so that the sheaves 21 and 22 may lie between the channels as indicated.

Journaled upon shaft 20 is a swinging yoke 23 which forms a guide for a dipper handle 24 which is conveniently made of two parallel spaced channels, one lying upon each side of the sheaves 21 and 22 45 and lying between the channels of boom 16, the arrangement being such that the dipper handle 24 is freely slidably in yoke 23 and is swingable about shaft 20 as an axis. The outer end of the dipper handle 24 carries a dipper 25 of any well known form and the details of which form no part of my present invention.

The upward retracting movement of the dipper handle is accomplished by a pull 50 back cable 26 in the present instance anchored to the outer end of the dipper han-

dle. Of course it will be understood that cable 26 may be associated with the dipper handle 24 in any desired manner so that a pull on the cable will serve to shift the dipper handle longitudinally inwardly. 60 Cable 26 passes over a sheave 27 journaled on boom 16, over a sheave 28 journaled at the lower end of the boom 16, thence down through table 11 at its axis and around sheave 29 to the winding drum 14. 65

For the purpose of swinging the dipper 25 upwardly and also crowding the dipper handle outwardly I provide a cable 30, 70 which is attached at its outer end to the upper inner end of the dipper handle, passes thence rearwardly around a sheave 31 at the lower end of the boom, thence forwardly around the sheave 22, thence up to and around a sheave 32 on the inner end 75 of the dipper handle, thence down and around sheave 21, thence back to a sheave 33, co-axial with sheaves 28 and 31, thence down through table 11 and around a sheave 34 co-axial with sheave 29 and thence to the winding drum 15. 80

It will, of course, be understood that the winding drums 14 and 15 will be provided with suitable controlling members by which they may be independently or simultaneously 85 controlled in their movements in either direction.

In operation a pull upon cable 30 by drum 15 will exert an outward thrust upon the dipper handle through the medium of the bight of the cable passing around sheave 32 and will also exert a swinging force upon the dipper handle through the medium of the outer end of the cable and its attachment through the upper inner end of the dipper handle. A combined swing and outward thrust may be accomplished by a gradual release of the cable 26 and outward thrusting movement may be eliminated by hanging on to cable 26 by braking drum 14. 95 100

I claim as my invention:

1. In an excavator, a boom, a dipper handle swingably and slidably mounted on said boom, a thrusting and lifting cable attached to the inner end of said handle and passed from thence around a sheave at the inner end of the boom, thence around a sheave further out on the boom, thence around a sheave at the inner end of the 110 handle, thence around a second sheave on the boom, and thence to a winding drum, 105

and means engaging the dipper handle to resist outward crowd and to shift the handle longitudinally inwardly.

2. In an excavator, a boom, a dipper handle swingably and slidably mounted on said boom, a thrusting and lifting cable attached to the inner end of said handle and passed from thence around a sheave at the inner end of the boom, thence around a sheave further out on the boom, thence around a sheave at the inner end of the handle, thence around a second sheave on the boom, and thence to a winding drum, and a second cable supported by the boom 10 and engaging the dipper handle to resist outward crowd and to retract the handle longitudinally.

3. In an excavator, a handled dipper, a support on which said handle is swingably 20 and slidably mounted, a main hoisting and crowding cable associated with the support and with the inner end of the handle to both swing and crowd it longitudinally in one direction, and means for resisting said 25 crowding movement, said means comprising a second cable attached to the outer end of the handle.

4. In an excavator, a handled dipper, a support on which said handle is swingably 30 and slidably mounted, a main hoisting and crowding cable associated with the support and with the inner end of the handle to both swing and crowd it longitudinally in one direction, and means for resisting said 35 crowding movement.

5. In an excavator, a handled dipper, a support on which said handle is swingably and slidably mounted, a main swinging and crowding cable associated with the support 40 and having a bight in end thrust engagement with one end of the handle for crowding it in one direction and another portion in swinging engagement with the same end of the handle, and means for resisting said 45 crowding action, said means including a cable attached to the other end of the handle.

6. In an excavator, a handled dipper, a support on which said handle is swingably and slidably mounted, a main swinging and 50 crowding cable associated with the support and having a bight in end thrust engagement with one end of the handle for crowding it in one direction and another portion in swinging engagement with the same end 55 of the handle, and means for resisting said crowding action.

7. In an excavator, a handled dipper, a support on which said handle is swingably and slidably mounted, a main swinging 60 and crowding cable associated with the sup-

port and having a bight in end thrust engagement with the inner end of the handle for crowding it outwardly and another portion in swinging engagement with the inner end of the handle and means for resisting 65 said outward crowd, said means including a cable attached to the outer end of the handle.

8. In an excavator, a handled dipper, a support on which said handle is swingably 70 and slidably mounted, a main swinging and crowding cable associated with the support and having a bight in end thrust engagement with the inner end of the handle.

9. In an excavator, a handled dipper, a support on which said dipper is swingably 75 and slidably mounted, a main swinging and crowding cable associated with said support and having one portion in crowding association with one end of the handle and another 80 portion in swinging engagement with the same end of the handle, and means for resisting said crowding, said means including a cable attached to the opposite end of the handle. 85

10. In an excavator, a handled dipper, a support on which said dipper is swingably and slidably mounted, a main swinging and crowding cable associated with said support and having one portion in crowding association with one end of the handle and another 90 portion in swinging engagement with the same end of the handle, and means for resisting said crowding.

11. In an excavator, a handled dipper, a support on which said dipper is swingably 95 and slidably mounted, a main swinging and crowding cable associated with said support and having one portion in crowding association with the inner end of the handle and another portion in swinging engagement with the inner portion of the handle, and means for resisting said crowding, said means including a cable attached to the outer end of the handle. 100

12. In an excavator, a handled dipper, a support on which said dipper is swingably and slidably mounted, a main swinging and crowding cable associated with said support and having one portion in crowding association with the inner end of the handle and another portion in swinging engagement with the inner portion of the handle, and means for resisting said crowding. 110

In witness whereof, I have hereunto set 115 my hand at Indianapolis, Indiana, this 6th day of January, A. D. one thousand nine hundred and twenty five.

ARTHUR M. HOOD.
